ASSIGNORS TO CHICAGO PNEUMATIC TOOL COMPANY, OF CHICAGO, ILLINOIS,
A CORPORATION OF NEW JERSEY.

ROCK-DRILL.

1,080,707.

Specification of Letters Patent.

Patented Dec. 9, 1913.

Application filed February 8, 1909. Serial No. 476,616.

To all whom it may concern:

Be it known that we, EDWIN M. MACKIE and PERCIVAL F. DOYLE, both residing at Franklin, Venango county, Pennsylvania, the former being a citizen of the United States and the latter a citizen of the Dominion of Canada, have invented certain new and useful Improvements in Rock-Drills, of which the following is a specification.

Our invention relates to rock drills and the object thereof is to provide therefor a continuous water or air service or intermittent water and air service, such water or air or both together being discharged through the drill steel to thoroughly clean the latter of all cuttings and the like, thereby increasing the cutting or drilling power by enabling the cutting end of the steel to strike on a clean surface at each blow and by enabling an easier rotation of such drill steel by the consequent absence of "mud" in the hole.

The various features of advantage and utility in our construction of rock drill with said means embodied therein will be apparent from the description hereinafter given.

In the drawings, Figure 1 is a central longitudinal section of a rock drill embodying our invention; Fig. 2 a front end elevation thereof; Fig. 3 an enlarged side elevation of the rifle bar nut; Fig. 4 an end elevation of such nut; Fig. 5 a central longitudinal section of a portion of the rock drill similar to Fig. 1 but on a larger scale; Fig. 6 a section on the line 6—6 of Fig. 5; Figs. 7 and 8 sections on the lines 7—7 and 8—8 respectively of Fig. 5; Fig. 9 a view of a modified form of construction as to one of the details; and Fig. 10 a view similar to Fig. 9 but showing a part thereof on a larger scale.

Referring to the present embodiment of our invention as illustrated in the drawings, the usual construction of rock drill is employed but modified in the several respects hereinafter referred to. As to the rock drill construction, it will be sufficient to state that such drill comprises essentially a cylinder 1, piston head 2 adapted to reciprocate therein and having a piston rod 3, the rifle or rotating bar 4 received by the chamber 5 in the rear end of the piston head, the rifle bar nut 6, thrust ring 7, ratchet ring 8 and a back-head 9. At its front end the piston 3 is suit-

ably constructed to carry and hold a drill steel 10. As usual, the main valve 11 is operated by means of the rocker 12, which in turn is actuated by the piston head in its movements, the main valve controlling the admission and exhaust of fluid pressure to and from opposite ends of the piston chamber within the cylinder through the passages 13 and 14.

The rock drill as just described is of the usual and well known construction, but is modified for the incorporation of our improvements in the manner now to be explained. The piston rod 3 is provided with a central longitudinal fluid passage 3^a which is adapted to communicate at its front end with a similar fluid passage 10^a extending longitudinally through the drill steel to the cutting end thereof. In practice, the inner end of the drill steel is received by a socket at the front end of the piston rod and packed by means of packing 15 to prevent any leakage of fluid pressure from the passage 3^a around the drill steel. The rifle bar is also provided with a central longitudinal passage 4^a which is in axial alinement with the passage 3^a. Within these passages 3^a and 4^a is arranged a stationary tube 16 secured in fixed position in suitable manner in the back head 9 and extending forwardly through the rifle bar and into the rear end portion of the passage 3^a, which is suitably counter-bored to receive it. This tube is of a sufficient length so that it will always project into the piston rod passage 3^a in whatever position such rod may be in its reciprocations. In the present instance the rear end of the tube is held in position in a central opening in the back head by means of packing 17 compressed against the tube by the packing nut 18. At the rear of the back head and by means of the end cap 19 is formed a fluid chamber 20 which communicates with the tube 16 and also with the fluid passage 21 in the back head, which in turn communicates with the pipe 22 connected with any suitable source of water or both water and air.

In the construction illustrated in Figs. 1 and 5 packing is provided between the passage 3^a and the tube 16, such packing in the present instance consisting of the two cupped leather packings 23 and 24 which are held within a packing box 25 and se-

cured therein by means of the screw-threaded packing retainer or gland 26 which clamps the meeting flanged portions of the packings against the bottom of the outer 5 socket of the box, the inner socket being arranged to receive the main portion of the packing 24. This packing and its packing box occupy the extreme front end of the rifle bar chamber 5 and the same are held in such 10 position by means of the bushing or sleeve 27 in such chamber, such bushing pressing against the rear face of the packing box, as clearly indicated in Figs. 1 and 5. This sleeve is itself held in position by means of 15 the rifle bar nut 6 screwing into the rear end of the piston head and by preference provided at the rear end with the angular notches 6^a for convenient application for tools for applying or removing such nuts, 20 Figs. 3 and 4. As shown, the two packings 23 and 24 are oppositely depressed so as to prevent the passage or leakage of fluid in either direction along the tube 16.

In practice the continuous water or air 25 service, or a service of mixed water and air, is provided by the operator through the supply pipe 22 which may be provided with suitable valve mechanism (not shown) for this purpose. The fluid thus admitted 30 through the supply pipe passes through the passage 21 in the back head to the chamber 20 and thence through the tube 16, and through the passages 3^a and 10^a to the front end of the drill steel.

35 In order to provide for an intermittent supply of water and air, only one cup leather packing 28, instead of the two packings 23 and 24, is employed, as shown in the modification, Fig. 9. This packing is so 40 arranged as to act as a check valve permitting the pressure to pass or leak by itself and along the tube and thence through the passages to the drill steel. The pressure here referred to as leaking past the packing 45 28 comes from the rear end of the cushioning space of the piston chamber, such space being indicated between the lines X Y. When the piston has closed the rear port 13 of the piston chamber, the fluid trapped therein 50 will become compressed by the further movements of such piston and such fluid thus compressed will pass or leak along the rifle bar and into the chamber 5, and will leak or pass along the tube 16 and also past 55 the single packing 28 in the manner already described. At the same time water is being admitted through the tube from the supply pipe 22, so that in the reciprocations of the piston an intermittent supply of water and 60 air will be forced through the fluid passages to the front end of the drill steel, the pack-

ing 28 acting as a check valve and preventing the return of pressure backwardly along the sides of the tool.

The construction and arrangement herein 65 before described are such that no appreciable or detrimental back pressure is created in practice in the fluid supply passages, but if desired a check valve might be interposed at any suitable point, as for instance in the supply passage as shown in the modification 70 in Fig. 9, wherein the check valve 29 is of the ball type and spring-pressed. However, where the working is in rock rich in mineral or sheet ore, or soil where there is a possibility 75 of the hole in the drill steel becoming plugged up with cuttings notwithstanding the flow of fluid therethrough, it is preferable to omit the check valve in order to prevent accumulation of pressure in the rifle 80 bar chamber which might eventually stop the machine or possibly burst the packings.

Although we have shown the check valve 85 in connection with the form of construction in which the single cupped leather packing is employed, it will be understood that such check valve may be employed in the other form of construction hereinbefore first described.

We claim:

1. In a rock drill, the combination of the cylinder, piston and rifle bar of such a drill, both the piston and bar having longitudinal passages and the piston having a rifle bar chamber, a tube arranged in said passages 95 and adapted to communicate with a source of fluid under pressure, and means for preventing back flow around the tube within the piston consisting of a removable box located at the front end of the rifle bar 100 chamber and having an opening for said tube, and packing arranged within said box and around the tube said box and packing being formed as a unit.

2. In a rock drill the combination of a 105 cylinder, piston, and rifle bar, both the piston and rifle bar having longitudinal passages and the piston having a rifle bar chamber, a tube arranged in said passages and adapted to communicate with the source of 110 fluid under pressure, packing means at the front end of the rifle bar chamber, means engaging the rear end of said packing means and holding the same in position and means engaging the piston head at the rear end 115 and engaging said first named means to hold it firmly against the packing.
